UNITED STATES PATENT OFFICE

GEORGE F. DUNICAN, OF ROCKVILLE CENTER, NEW YORK, ASSIGNOR TO THE NATIONAL CASKET COMPANY, INC., OF BOSTON, MASSACHUSETTS, A CORPORATION OF NEW YORK

DESIGN FOR A TEXTILE FABRIC OR SIMILAR ARTICLE

Application filed July 7, 1931. Serial No. 40,450. Term of patent 7 years.

To all whom it may concern:

Be it known that I, GEORGE F. DUNICAN, a citizen of the United States, residing at Rockville Center, Long Island, in the county of Nassau and State of New York, have invented a new, original, and ornamental Design for a Textile Fabric or Similar Article, of which the following is a specification, reference being had to the accompanying drawing, forming part thereof.

The figure is a plan view showing the pattern of my new design.

I claim:

The ornamental design for a textile fabric or similar article as shown.

GEORGE F. DUNICAN,
